APPARATUS FOR BENDING METAL

Daniel Kelleher, Strongsville, Ohio, assignor to
The American Coach & Body Company, Cleve-
land, Ohio, a corporation of Ohio

Application November 21, 1942, Serial No. 466,421

5 Claims. (Cl. 153—76)

This invention pertains to an apparatus for making alternate ridges and grooves in sheet metal plates and in regular formation with substantial parallelism.

Where a plate is to be corrugated of relatively heavy sheet material, particularly where the corrugations comprise angular ridges and grooves, considerable difficulty has been experienced in making a large number of corrugations simultaneously, because the metal is stretched to an objectionable degree, even to the extent of being torn apart.

An object of the present invention is to provide for making corrugations which will not damage the material of which the sheet is made, and which will not require an expensive die for forming the corrugations. Additionally, an object is to utilize an apparatus by means of which the corrugations are made progressively whereby the material is bent only sufficiently to make one corrugation at a time.

The invention contemplates means whereby a machine known as a "brake" can be utilized for making successive corrugations across the face of a sheet, and includes mechanism by means of which one corrugation acts as a pilot for automatically clamping the sheet in position for making succeeding corrugations. This assures absolute uniformity and parallelism of the respective ridges and grooves.

Referring now to the drawings, Fig. 1 is a front view of a machine designated as a "brake" in which my invention may be practiced; Fig. 2 is an end view of the machine showing a portion of the control mechanism; Fig. 3 is a section taken on the plane designated by the line 3—3 in Fig. 2; Fig. 4 is a front view showing the foot-operated pedal which is used with the control mechanism; Fig. 5 is a vertical section taken on a scale larger than that shown in Fig. 1 and illustrates the first step in the preferred method of forming the corrugations; Fig. 6 is a sectional view similar to a portion of that of Fig. 5 and illustrates the beginning of the second step; Fig. 7 is a vertical section similar to that shown in Fig. 5 but illustrates a further step in the formation of the second corrugation; Fig. 8 is a vertical section showing the completion of the step which is indicated in Fig. 7; Fig. 9 is a perspective view of a plate showing the finished corrugations, and Fig. 10 is a section view through a modified arrangement by means of which the plurality of corrugations can be made progressively during a single reciprocation of the ram.

In Fig. 1, I have shown a machine commonly

designated as a "brake" which has a base or stationary press head 10, a frame 11, and a ram or movable press head 12. Preferably, the movable head carries a single die 13, while the stationary head carries a plurality of dies, one indicated at 14 as being relatively stationary, and another designated at 15 as being relatively movable. The present invention is illustrated as having dies formed to make a corrugated sheet such as that shown in Fig. 9, and the invention embodies an efficient mechanism which will permit the formation of one corrugation and the utilization of it as a pilot to position the sheet for the formation of a succeeding corrugation.

The sheet illustrated in Fig. 9 has regularly formed ridges A and depressions B which are uniformly spaced, and are disposed in parallelism in any desired number across the sheet. The sheet is illustrated as being rectangular in form, but that is not material so far as carrying out the process is concerned. Any shape may be utilized for obtaining the desired result.

The apparatus utilized for carrying out the present invention is shown in preferred form in Figs. 1 to 8, inclusive, wherein the upper die (Fig. 5) has grooves 13a and 13b therein, and wherein the lower die 14 has a projection 14a, the shape of which is complementary to the groove 13a in the upper die. The lower die 15 also has a projection 15a, the shape of which is complementary to the groove 13b in the die 13. The die 15 functions as a pilot die for positioning the plate automatically and clamping it in position preparatory to the formation of the adjacent corrugation as will hereinafter be set forth in detail. Suitable mechanism is also provided for automatically effecting the clamping and positioning of the sheet, consequent upon actuation of the mechanism for operating the ram, all as will hereinafter be set out in the following description.

The first step, according to the preferred method, in forming the corrugations is to slide the sheet S, while it is held in a horizontal position, between the dies 13 and 14, with the forward end 45 thereof disposed beyond the ridge of the projection 14a by a predetermined amount sufficient to form the end wall of the first corrugation. The extent of such inward movement of the sheet is ascertained by means of a gauge that is disposed on the machine, but not shown herein. It is sufficient to say, merely, that the sheet rests only on the projection of the die 14 when the ram is in the uppermost position as shown in Fig. 5. Thereupon, the ram controlling mechanism is actuated to lower the ram, thus bringing

the die 13 downwardly into engagement with the sheet S and then bending it about the ridge of the die 14, and altering the shape of the sheet from the full line position in Fig. 5 to the dotted line position Sa in Fig. 5. During that motion of the ram, the pilot die 15 remains idle.

In Fig. 6 I have shown the die 13 as being held above the dies 14 and 15, and I have shown the sheet Sa as being moved forwardly in the direction of the arrow to a position where the first corrugation is disposed approximately over the pilot die 15, and the sheet is resting in horizontal position on the projection 14a. Thereupon, the pilot die is caused to be raised to the position shown in Fig. 7 until the projection 15a thereon enters the underside of the first corrugation, and thereby automatically centers it in position for the succeeding corrugation.

While the sheet is held, as shown in Fig. 7, and during the upward motion of the pilot die, the ram is lowered, the first contact between the die 13 and the sheet occurring between the upper surface of the first corrugation and the walls of the groove 13b. The force utilized for holding the pilot die upwardly is yieldable and is less than that exerted by the ram; hence, the pilot die is forced downwardly by the ram until the groove 13a acts upon that portion of the sheet resting upon the projection 14a, whereupon the pilot die is moved downwardly under continued motion of the die 13 until the second corrugation is formed as is shown in Fig. 8, making the sheet Sb. Thereafter, the same operation is repeated with the last formed corrugation being disposed over the pilot die as shown in Fig. 6 until the desired number of corrugations is formed.

By clamping one corrugation between the upper die and the pilot die, then as the succeeding corrugation is being formed, the sheet will be drawn inwardly sufficiently to provide adequate material to compensate for the reduction in overall length of the sheet, thereby avoiding any stretching of the material that would in any way tend to reduce the cross sectional area of it. Additionally, the clamping action automatically holds the sheet in the exact position required for forming the succeeding corrugation. Thus, the method permits any number of corrugations to be made by utilizing one corrugation as an automatic guide for positioning the sheet.

The mechanism which is preferred for controlling the operation of the ram and of the pilot die is illustrated as embodying a foot pedal 30 which is disposed in front of the machine and in a place that is convenient for the use of the operator, and which is shown as having arms 31 extending downwardly from the underside thereof and attached to a bracket 32 by means of a pivot pin 33. Such pivot allows the pedal to be swung about the arc indicated by the arrow 34 in Fig. 4. The end of one of the arms 31 is shown as being tapered to a point for engagement with a spring-like inverted V-shaped member 35 that is yieldable to permit the end of the arm to pass beyond the ridge thereof, but is capable of retaining the arm in the last position in which it was placed with respect to the center of the ridge.

The foot pedal is also capable of being swung forwardly and backwardly as indicated by the arrow 36 in Fig. 2, and to this end the bracket 32 is shown as embracing a rod 40 which may extend the entire length of the front end of the machine and be supported in bearings 41 and

42 respectively, adjacent opposite ends of the machine. The rod 40 may have a hexagonal shape between the bearing points, so that the bracket may be disposed in any position thereon and clamped thereto as by means of bolts 45. The rod 40 is illustrated at the right hand end of Fig. 1 as being suitably connected to a vertically extending rod 46 which actuates the clutch mechanism for operating the ram in any well known manner. A spring 47 disposed at the side of the machine may be used as a convenient means for returning the pedal back to its original position after it has been operated to actuate the ram.

If desired, the mechanism for actuating the pilot die may be incorporated in the mechanism for actuating the ram and for such purpose the rod 50 may have adjacent the pedal, a sleeve 51, rigidly attached thereto, while a stud carried by the sleeve may project laterally through the arm 31 and constitute a pivotal connection therewith. Thus, whenever the pedal is oscillated in the direction indicated by the curved arrow 34 in Fig. 4, the rod 50 is moved to the right or to the left as shown by the straight arrow 55 in Fig. 4.

To actuate the pilot mechanism upon operation of the rod 55, the end of the rod 50 opposite the pedal (Figs. 2 and 3) may be slidably mounted in an opening of an arm 60 that is illustrated as being rigidly attached to a bracket 61. The bracket may be rigidly secured at 62, as by welding, to a yoke 63, which in turn may be fastened, as by bolts 64, to the rod 40. The arm 60 also has an opening for guiding a pin 65 which is carried by a plate 66 that is rigidly secured to the end of the rod 50, and has substantially the same shape as the plate or arm 60. When the plate 66 is in the full line position of Fig. 3, the pin 65 extends beneath an arm 70 which controls suitable valve mechanism for governing the flow of fluid to two cylinders 71 that are disposed near the ends of the pilot die 15, as may best be seen in Fig. 1.

The valve mechanism controlled by the arm 70 may be of any well known type, there being two valve casings shown at 72 and 73 that are so connected to the cylinders that the casing 72 controls the admission of fluid to the bottom of the cylinder 71, as well as the exhaust therefrom, while the valve 73 controls the admission of fluid to the top of the cylinder 71, as well as the exhaust therefrom, the arrangement being such that fluid is admitted simultaneously to the bottom of each cylinder for raising the piston 75 therein, while fluid is being exhausted from the top of each piston so as to facilitate the upward movement thereof. As the pistons travel upwardly, their piston rods 76 move upwardly correspondingly and exert an upward force against the bases 77 of tap rods 78. Normally, when the pistons are at the bottom of their stroke, the tops of the rods 78 are spaced from the bottom of the pilot die 15, but as the pistons rise, the rods engage the die 15 and lift it upwardly from the position shown in Fig. 5 to the position shown in Fig. 7.

So long as the operating parts are in the position shown in Fig. 7, and so long as the operator depresses the pedal downwardly in the direction of the curved arrow 36 in Fig. 2, fluid pressure is maintained beneath the pistons 75 and at the same time the ram 12 is moving downwardly to form a corrugation. Accordingly, the operator maintains the pedal depressed until the corruga-

tion is formed, whereupon he releases it and allows it to be returned automatically under the force of the spring 47 to the position shown in Fig. 2. At such time, the fluid is exhausted from the bottom of the pistons 75 and is injected against the top portions thereof.

During the downward movement of the pilot die 15 under the force exerted by the upper die 13, the rods 78 and their corresponding pistons are forced downwardly, but inasmuch as the operator continues to maintain the foot pedal depressed, there is a yielding force pushing upwardly against the die so as to maintain firm contact against both sides of the sheet during the formation of the adjacent corrugation.

Whenever the fixed die 14 is used for forming the first corrugation, it is not necessary to move the pilot die upwardly, hence, the ram can be operated without moving the pilot die by disengaging the pin 65 from contact with the arm 70 during the oscillating movement of the bar 40. This may be attained by sliding the rod 50 axially to the left in Fig. 1, so that the plate 66 (Fig. 3) assumes the broken line position 66a. In such position the end of the pin 65 is caused to move out of the path of the arm 70, but to remain within the aperture in the plate 60.

While I have described my invention as embodying the step of making an end corrugation and then using that as a pilot for positioning the seat so as to form the succeeding corrugation, I may, if desired, move the sheet in the first instance across the fixed and pilot dies and thereby use the fluid pressure beneath the pistons 75 to form the first corrugation on the pilot die, and then on the continued downward motion of the ram, to form the second corrugation over the fixed die, so that initially two corrugations are made successively in point of time, but in one reciprocation of the ram. For example, the sheet would be initially positioned as shown at the dotted lines Sc in Fig. 7. In that modification, it would not be necessary to utilize the disengaging mechanism which is employed where the first corrugation is made on the fixed die.

Where the pilot die is used conjointly with the fixed die for making two corrugations initially, it is not necessary to move the pedal 30 in a way that would disengage the pin 65 from contact with the arm 70, because upon every reciprocation of the ram, the vertical movement of the pilot die would be desired.

In Fig. 10, I have shown a modification of my invention where I have carried forward the suggestion of utilizing the pilot die in conjunction with the fixed die for making two corrugations initially by employing a plurality of movable dies designated 80, 81, 82, and 83, together with a fixed lower die 84 and a movable upper die 85. If desired, individual cylinders could be employed for raising the pilot dies 80 to 83, inclusive, but for the purpose of minimizing the illustrative mechanism, I have shown a common fluid chamber 90 with a source of supply from a conduit 91 for increasing fluid under pressure beneath the respective pilot dies, and utilizing shoulders 92 on the dies for limiting upward movement of one with respect to the other. The view shown in Fig. 10 illustrates the sheet Sd as having had the first corrugation made over the fixed die 80 and as being thereafter moved into position for having the succeeding four corrugations progressively formed. In this modification, however, the corrugations are formed progressively as before, one of the corrugations acting as a pilot

for positioning the sheet in proper location for the formation of a succeeding corrugation.

An advantage of my invention is the fact that any number of corrugations may be quickly made on a machine with a minimum expense for dies, and without the necessity for much attention by the operator to position and clamp the sheet in the proper location. Additionally, the invention permits multiple formation of corrugations without stretching the material, and independently of the overall shape of the sheet that is being corrugated. The invention is thus well adapted for production requirements, and is instrumental in the attainment of an economical procedure as a method of manufacture.

I claim:

1. In a press for forming successive deformations in sheet material, two press heads and means to move them toward each other, fixed dies carried by the heads and adapted to produce a deformation in a sheet, a movable die carried by one head, fluid pressure means to move the last named movable die toward the other head whereby such movable die and the fixed die on the other head may clamp the sheet at a previously formed deformation, as the heads are moved together, and before and during the succeeding deformation by the fixed dies, a valve to control the fluid pressure means having an operating handle, a control shaft, an operating lever for rocking the control shaft to initiate the head moving means, an arm secured to said shaft and having a portion engageable with said valve operating handle, a link between the operating lever and said portion, the operating lever having a freedom of movement in addition to its shaft rocking movement whereby to move the link and thus to maintain said portion in or out of engagement with the valve handle.
2. In a press for deforming sheet material, two press heads and means to move them to press closing position, dies on the heads, one of which is movable relative to its respective head, fluid pressure means to move the movable die toward the other head in addition to the press closing movement, a rock shaft operable to control the press closing means, an operating lever for rocking the shaft having a pivotal mounting thereon for an additional movement longitudinal of the shaft, a fluid valve controlling said fluid pressure means and having an operating handle, an arm secured to the rock shaft, a pin slidable in the arm and connected to said operating lever, said valve handle being in the path of movement of the pin as the shaft is rocked in or out of such path as determined by the position of the operating lever upon its pivotal mounting, whereby the press closing means may be operated with or without an attendant movement of the movable die.
3. A press having in combination, a stationary press head and a movable press head, a single die carried by the movable press head and having a plurality of faces rigid with each other and a plurality of dies carried by the stationary press head, means for moving the movable press head, fluid actuated means for moving one of the dies on the stationary press head with respect to the other die, and yieldingly maintaining it while projected variable amounts beyond the other die, and a member for selectively actuating the movable press head with or without actuation of the movable die on the stationary press head.
4. An apparatus for forming corrugations in sheet material, comprising a relatively station-

ary and a relatively movable lower die disposed in side-by-side relationship with their crests in horizontal alignment, and a movable upper die having two faces rigid with each other and respectively registering with the lower dies, means for moving said upper die against a sheet adapted to be interposed between the lower and upper dies, controlled means for projecting the movable lower die upwardly beyond the other lower die to effect engagement between the sheet thereon and one face of the upper die before contact is effected between the sheet and the remaining face of the upper die, the last-mentioned means operating to permit yielding movement of the movable lower die under the force exerted by the closing movement of the upper die, and a single control for actuating both of said means.

5. An apparatus for forming corrugations in sheet metal having in combination two coacting members, one comprising a bed and the other a ram reciprocable toward and from the bed, a bracket comprising a base and an upright secured to one of said members, a relatively stationary die mounted on the base and spaced from the upright and one or more movable dies between the stationary die and the upright, controlling means for projecting the movable die or dies beyond the stationary die and yieldingly supporting said projecting die or dies, and a die carried by the other of said members and formed with a plurality of faces to coact respectively with the stationary die and movable die or dies first-mentioned.

DANIEL KELLEHER.
